UNITED STATES PATENT OFFICE.

THOMAS COOPER, OF KIDDERMINSTER, ENGLAND.

TUFTED PILE FABRIC.

No. 818,951.

Specification of Letters Patent.

Patented Feb. 27, 1906.

Application filed June 19, 1905. Serial No. 266,036.

To all whom it may concern:

Be it known that I, THOMAS COOPER, a subject of the King of Great Britain, residing at Farfield, Kidderminster, England, have invented certain new and useful Improvements in Tufted Pile Fabrics, of which the following is a specification.

My invention consists of the improvements hereinafter described in tufted pile fabrics— such, for example, as Axminster or moquette carpets and rugs—the said improvements having for their objects to give to the said fabrics the character or appearance of Turkey or oriental carpets and rugs, in which carpets and rugs the pattern or design is the same on the back or under side of the carpets and rugs as on the upper side or face and to simplify the weaving of such imitation Turkey or oriental carpets and rugs.

Heretofore many attempts have been made to produce in looms for weaving tufted pile fabrics carpets and rugs resembling Turkey or oriental carpets and rugs; but the previous attempts referred to have not been attended with great success, the several binding-warps employed being conspicuous on the under side or back of the fabric and effecting a compressing of the doubled parts of the tufts, so that the pattern or design is not as conspicuous on the back as on the pile-face of the fabric.

By the arrangement or combination hereinafter described of the threads and tufts of the fabric a tufted pile fabric is produced in which the pattern or design is as well defined or marked on the under side or back as on the pile-face, the cut-pile surface alone distinguishing the upper from the under side.

In the tufted pile fabric constituting my invention the warps, wefts, and tufts are arranged as is hereinafter described with reference to the accompanying drawings, of which—

Figure 1 represents in longitudinal section a piece of the improved tufted pile fabric, the section being taken in a plane, so as clearly to show the binding-warp. Fig. 2 represents a longitudinal section taken through the tufts of the fabric. Fig. 3 represents in plan the warp and weft threads of the fabric, the tufts constituting the pile being omitted.

In the said fabric each set or series of warps consists of an approximately-straight

warp *a*, preferably of cotton, two straight warps, (marked *b*¹, respectively,) preferably of jute, and a single binding-warp *c*, preferably of linen, which in its course through the fabric passes between the pair of straight warps *b*¹. With the said warps three shots of weft are employed, (marked, respectively, *d*¹ *d*² *d*³.) The upper shot of weft *d*¹ passes over the approximately-straight warps *a*. The middle shot of weft *d*² passes between the warps *a* and the warps *b*¹, and the third shot of weft *d*³ passes under the straight warps *b*¹. The tufts *e*, constituting the pile, are doubled on the lower shot of weft *d*³. The single binding-warps *c* employed pass under the lower shots of weft *d*³ and over the upper shots of weft *d*¹.

I wish it to be understood that I do not limit myself to threads of the materials hereinbefore mentioned for the warps. For example, jute threads may be employed for the warps *a*, when the said warps *a* will be straight and without the kinks illustrated in Figs. 1 and 2. Further, I wish it to be understood that for the sake of clearness I have represented the warps of uniform thickness; but it will be understood by those conversant with the manufacture of carpets and rugs that this is not so, the binding-warps *c* of linen thread being much finer than the warps *a* *b*¹.

By the arrangement or combination of threads and tufts hereinbefore described and illustrated not only are the doubled portions of the tufts on the under side of the fabric permitted to spread out so as practically to conceal the warp-threads and render the pattern or design as plain or conspicuous on the back as on the pile-face of the fabric, the improved tufted pile fabric resembling closely Turkey or oriental carpets and rugs, but a simpler and more efficient binding of the tufts is effected than is usually obtained in tufted pile fabrics of this class.

Having now described my invention, what I claim as new, and desire to secure by Letters Patent, is—

A tufted pile fabric of three-shot weft, the tufts being doubled on the lower shots of weft; the warps of which fabric are in series of four threads, one warp of each series of four threads being straight or approximately straight and being arranged under the top

shot of weft, a pair of straight warps being situated under the middle shot of weft and a fourth thread or binding-warp passing under the lower shots of weft and over the upper 5 shots of weft and between the last-named pair of straight warps substantially as set forth and shown.

In testimony whereof I have hereunto set my hand in presence of two subscribing witnesses.

THOMAS COOPER.
